(57) CLAIM

I claim the ornamental design for the footwear, as shown and described.

DESCRIPTION

FIG. 1 is a front view of the footwear.

FIG. 2 is a rear view of the claimed design.

FIG. 3 is a right side view of the claimed design.

FIG. 4 is a left side view of the claimed design.

FIG. 5 is a top view of the claimed design.

FIG. 6 is a bottom view of the claimed design; and,

FIG. 7 is a perspective view of the claimed design.

The phrase "bad dog" appearing on FIG. 1, FIG. 3, FIG. 5 and FIG. 7 is environmental matter forming no part of the claimed design.

1 Claim, 5 Drawing Sheets
